UNITED STATES PATENT OFFICE.

LUCIUS E. WEAVER, OF EAST HAMPTON, CONNECTICUT, ASSIGNOR TO SUMMIT THREAD COMPANY, OF EAST HAMPTON, CONNECTICUT, A CORPORATION OF MAINE.

ADJUNCT FOR SEWING-MACHINE SHUTTLES.

1,421,873.

Specification of Letters Patent. Patented July 4, 1922.

Application filed February 28, 1921. Serial No. 448,689.

To all whom it may concern:

Be it known that I, LUCIUS E. WEAVER, a citizen of the United States, residing at East Hampton, in the county of Middlesex 5 and State of Connecticut, have invented new and useful Improvements in Adjuncts for Sewing-Machine Shuttles, of which the following is a specification.

This invention relates to a shuttle which 10 includes a bobbin case, having a post adapted to support and permit the rotation of a universally wound bobbin.

The object of the invention is to provide 15 an adjunct adapted to be quickly applied to and removed from the bobbin-case post, and to prevent undesirably loose rotation of the bobbin, and undesirably loose endwise movement thereof, so that the delivery of thread 20 by the bobbin will not exceed the call for the thread, and the bobbin is not liable to drop off from the post when the shuttle case is held in position for the bobbin to gravitate from the post.

The invention is embodied in the im- 25 proved adjunct hereinafter described and claimed.

Of the accompanying drawings forming a part of this specification,—

Figure 1 is a side view of a central bobbin shuttle, without the bobbin case.

Figure 2 is a section through the shuttle on the plane line 2—2 of Figure 1, the bobbin case and bobbin thereon, and an adjunct embodying the invention being shown in 35 section on the same plane.

Figure 3 is a section on line 3—3 of Figure 2.

Figure 4 is a perspective view of my improved adjunct.

40 The same reference characters indicate the same parts in all of the figures.

In the drawings I have illustrated the invention as an adjunct of the bobbin case of a Singer central bobbin shuttle, the shuttle body 12 being provided with the usual stud 13, on which the usual tubular post 14 of the bobbin case 15 is adapted to rotate.

It is customary to employ universally 50 wound bobbins in shuttles of this character, the bobbin including a core 16, which is usually a tube of paper, and a winding 17 of thread universally wound on the core. The core has a somewhat loose fit on the bobbin- 55 case post 14, so that when the case is re-

moved from the shuttle stud 13, and is being manipulated and held in various positions, the bobbin is liable to drop from the post 14, the fit of the bobbin core on the post being so loose that the bobbin is free to 60 move endwise by gravity, when the post is inclined downward from the closed end of the case 15.

In carrying out my invention I provide a 65 resilient split sleeve 18, made from relatively thin resilient sheet metal, the thickness of the metal being such that the sleeve is adapted to be interposed between the post 14 and the bobbin core 16, without requiring any enlargement of the core to 70 accommodate the sleeve. The edges 18^a of the sleeve normally abut against each other, the diameter of the sleeve being such that when it is placed upon the post 14, the sleeve is somewhat expanded, so that its 75 edges are more or less separated, and the sleeve, by reason of its effort to contract, has a close frictional bearing upon the post 14, the frictional contact of the sleeve with the post being such that the sleeve does not 80 rotate with the bobbin, and constitutes an unyielding bearing on which the bobbin core is adapted to rotate.

The sleeve is provided with a resilient tongue 19, formed by cutting the sleeve to 85 form an opening, the tongue being integral with the sleeve, and joined thereto at one end of the opening. The tongue is normally inclined outward from the periphery of the sleeve, as shown by Figure 4. As indicated by Figure 3, the tongue is adapted to be pressed inward, into the opening and flush with the periphery of the sleeve, by the bobbin core 16. The effort of the tongue 90 19 to assume its normal position shown by Figure 4, causes the tongue to bear yieldingly on the bobbin core and prevent undesirably loose rotation and undesirably loose endwise movement of the bobbin.

It will be seen from the foregoing, that 100 the sleeve constitutes an adjunct which is readily applicable to the post of a bobbin case, the application of the sleeve requiring no modification, either of the post or the bobbin core, and that when the sleeve is in 105 use, it controls the bobbin and prevents liability of accidental separation thereof from the case. The frictional hold of the sleeve on the bobbin-case post enables it to remain in engagement with the post when 110

the bobbin core is removed, so that the sleeve is always in readiness to be engaged with the core of a fresh bobbin replacing the removed core of a spent bobbin.

5 The sleeve may be formed so that its edges 18^a will be considerably spaced apart when the sleeve is engaged with the post 14, so that the sleeve may be used in connection with a bobbin case of the type shown 10 by the Porter Patent No. 832,414, of October 2, 1906. The case of this patent has a longitudinal slot in its post, and a bobbin-ejecting finger projecting laterally from within the post, through the slot, and engaging 15 the inner end of the bobbin to partially eject the latter from the case. The ejecting finger of the Porter patent may be projected between the edges 18^a of the sleeve 18.

I claim:

20 A bobbin-controlling adjunct for a bobbin case having a central post; said adjunct

comprising a split sleeve of thin resilient material having an opening in one side, and adapted to fill an annular space between said post and a bobbin core; and a resilient 25 tongue joined to the sleeve at one end of said opening, normally inclined outward from the sleeve, and adapted to be pressed into said opening, the sleeve being normally of smaller diameter than said post, and adapted to be expanded by and frictionally 30 hug the latter to resist movement of the sleeve on the post, the sleeve, when expanded by the post, being adapted to closely fit the internal surface of a bobbin core, and 35 the tongue being adapted to be forced by the core into said opening, and to exert a yielding outward rotation-resisting pressure on the core.

In testimony whereof I have affixed my 40 signature.

LUCIUS E. WEAVER.
